UNITED STATES PATENT OFFICE.

FRANK B. BIRCH, OF PHILADELPHIA, PENNSYLVANIA.

PACKING FOR JOURNAL-BOXES.

1,103,025.

Specification of Letters Patent. Patented July 14, 1914.

Application filed October 15, 1912. Serial No. 725,845.

To all whom it may concern:

Be it known that I, FRANK B. BIRCH, a citizen of the United States, residing in Philadelphia, Pennsylvania, have invented 5 certain Improvements in Packing for Journal-Boxes, of which the following is a specification.

The object of my invention is to provide a packing for journal boxes which will perform its intended function more acceptably 10 than the mass of fibrous waste usually employed for this purpose, an object which I attain in the manner hereinafter set forth, reference being had to the accompanying 15 drawing, in which—

Figure 1 is an outside view of a body of packing prepared in accordance with my invention; Fig. 2 is a longitudinal section of the same, and Fig. 3 is a transverse section, 20 on a smaller scale, of a journal box with the mass of packing disposed therein.

The mass of fibrous waste usually inserted in the lower portion of a journal box for the purpose of conveying the lubricant 25 therein to the exposed portion of the journal does not effectively perform this function because, owing to its lack of resiliency, it does not at all times maintain itself in contact with the journal and thus fails to 30 properly apply the lubricant to the latter. Moreover, the proper application of the mass of waste in the first instance is one requiring considerable care and skill, and when it becomes necessary to remove the 35 mass the latter cannot be readily taken out as a unit but must be picked out by a hooked implement, so that both the packing and the repacking of the journal box requires considerable time.

40 The object of my invention is to overcome these objections and this object I accomplish by providing a unitary mass or body of packing which can be introduced into or removed from the box without loss 45 of time, and which possesses a considerable degree of resiliency, so that it will maintain itself at all times in contact with the journal and will consequently provide for the proper application of the lubricant to the 50 latter.

The packing material is composed of masses of waste yarn or fiber 1, preferably of wool, bound together by convolutions 2 of wire running from end to end of the 55 mass, first in one direction and then in the opposite direction, so as to cross each other

and become interwoven in the mass, as shown in Fig. 1, the mass having a central opening 3 extending through the same from end to end, as shown in Fig. 2. In building up the body of packing masses of the yarn or fiber waste are applied in succession to a rotating spindle and are bound in place thereon by the successive convolutions of the wire, the application of the mass of yarn 60 or fiber and the wrapping of the convolutions of wire around the same being continued until a body of the desired bulk has been produced, the masses of waste being, by preference, so distributed during the operation that the body will be of greatest diameter at the center and will taper toward each end, as shown in Figs. 1 and 2. When the operation has been completed the mass is removed from the spindle so as to produce 70 the central longitudinal opening 3.

Besides the natural resiliency of the material constituting the textile body, the resiliency of the latter is further enhanced by the resiliency of the wire coils whereby the 80 component portions of the textile body are bound together, and still further by the hollow character of the mass due to the presence of the central longitudinal opening 85 therein, consequently, when the packing body is introduced into the lower portion of a journal box 4, as shown in Fig. 3, its resiliency will cause it to press closely against the exposed under side of the journal 5 at all times, the tapering shape of the body, permitting it to adapt itself to the shape of the space in the journal box available for its reception without risk of compressing the end 90 portions of the mass in the relatively contracted spaces between the sides of the journal and the sides of the box to such an extent as to interfere with the free passage 95 of the lubricant through these portions of the mass, or to detract from the capillarity of the fibrous bodies of which the mass is composed, the result being the effective application 100 of the lubricant to the exposed portion of the journal until the body of lubricant with which the box is supplied has been practically exhausted.

I claim:

1. A journal box packing consisting of a hollow-cored mass of textile fibers disposed in successive superposed layers, each bound by a coil of wire extending throughout its 110 length and having the same longitudinal axis as the mass of fibers.

2. A journal box packing consisting of a mass of textile fibers disposed in successive superposed layers, each bound by a coil of wire extending throughout its length and having the same longitudinal axis as the mass of fibers, the convolutions of some of the coils being wound in one direction and those of the alternate coils being wound in the opposite direction.
- 10 3. A journal box packing consisting of a hollow-cored mass of textile fibers disposed in successive superposed layers, each bound by a coil of wire extending throughout its

length and having the same longitudinal axis as the mass of fibers, the diameter of the fibrous mass and of the series of coils decreasing from the center toward each end of the mass. 15

In testimony whereof, I have signed my name to this specification, in the presence of 20 two subscribing witnesses.

FRANK B. BIRCH.
